R. Mitchell.

ATTORNEY.

UNITED STATES PATENT OFFICE.

MARY HEATH, OF NEW YORK, N. Y.

ABDOMINAL BANDAGE.

SPECIFICATION forming part of Letters Patent No. 514,930, dated February 20, 1894.

Application filed March 28, 1893. Serial No. 467,940. (No model.)

To all whom it may concern:

Be it known that I, MARY HEATH, of the city, county, and State of New York, have invented a new and useful Abdominal Bandage, 5 of which the following is a full, clear, and exact specification.

My invention consists in the novel construction of the parts hereinafter fully shown and described.

10 The object of my invention is to provide an abdominal bandage that shall closely conform to the curves of the body and that will not wrinkle or lose its shape.

15 My invention is illustrated by the accompanying drawings, in which—

Figure 1 is a perspective view of my abdominal bandage showing said bandage secured in position upon the person. Fig. 2 is an enlarged rear view of the bandage, and 20 Fig. 3 is a horizontal cross-section on the line 3—3 Fig. 2.

A is the body portion of the bandage which may be made of any suitable material, but preferably a fabric of a woolen nature. This 25 bandage tapers toward the ends, its widest part being at or near the middle of the bandage. Both ends of the bandage are provided with button-holes B, or other suitable means to be used to secure the bandage in position.

30 D D are elastic bands interposed in the bandage at or near the ends, for the purpose of giving an elasticity or stretch to the bandage. If preferred, instead of elastic bands, a woven elastic fabric may be used.

35 G G are ribs or stays preferably made from whale-bone. Said stays are secured in the body portion A of the bandage, vertically, for the purpose hereinafter described.

40 F is a binding extending along the edge of the body portion A of the bandage. This binding is made of a material that will not permit of as much stretch as the material forming the body portion.

45 H H are buttons secured to the outside of the bandage for the purpose hereinafter described.

J is a vertical slot cut in the bandage at a point adjacent to one set of the stays or ribs G G for the purpose hereinafter described.

50 It will now be seen that by stretching this bandage, the grasp being had at both ends of the bandage, the tendency will be to draw the two strips of binding F F which extend

along the edge of the bandage into a straight line, and inasmuch, as before stated, as the 55 bandage is wider at the center than at the ends, the binding F will tend to slightly buckle the ribs G G, (the ends of which preferably extend into the binding) and thereby give a contour to the bandage, even while the 60 bandage is not in place. It will therefore be seen that a bandage thus constructed will fit more naturally to the contour of the body than devices of the same class, but of different construction.

65 As shown by the drawings, the slot J affords a means whereby one end of the bandage may be passed through to the outside of said bandage when in position, so that it may be secured by buttons or other fastening devices. 70 I preferably use the elastic bands D D in place of a solid elastic web, so that I do away with the double thickness of fabric at the point where the bandage would otherwise be of double thickness. An advantage is gained 75 by having one set of ribs G G at a point adjacent to the slot J for the reason that it prevents the bandage from puckering or wrinkling at that point.

Having thus described my invention, what 80 I claim, and desire to secure by Letters Patent, is—

1. The combination of an abdominal bandage consisting of an elastic body A broadest about midway in its length and tapering toward each end, with a substantially non-elastic binding running around the entire device, with the sets of vertical ribs G G, and a slot J formed between the ribs of one of the sets of ribs, said slot extending from the binding 85 piece on one edge to the binding piece on the other edge, and with means for adjusting said bandage, substantially as and for the purpose 90 specified.

2. An abdominal bandage consisting of the 95 body A, provided with elastic ribs G and bindings F F of non-stretchable material for the purpose of causing said bandage when under tension to curve to more naturally fit to the contours of the body, and elastics D D, substantially as described.

MARY HEATH.
